PREFABRICATED CUBIC UNITS FOR SMALL HOUSES

Karl H. Brunner, Bogota, Colombia

Application June 17, 1936, Serial No. 85,805

12 Claims. (Cl. 20—1)

The present invention relates to improvements in prefabricated cubic units for small houses and has for an object to accomplish prefabrication of a house to such an extent that the completion of the house requires only the building of a foundation, assembly of the units and making the usual connections with gas, water etc.

Another object is to provide building units which are readily transportable and easily and cheaply assembled and disassembled.

A further object is the provision of building units which may be assembled without the use of cranes and the like.

Another object is the possibility of enlarging a completed house by the addition of further units; or modification of the existing plan of a set of assembled units.

Another object is to allow the building of a prefabricated house which has hitherto unattainable architectural beauty.

Further objects include building the units to conform with the gauge of railroads to facilitate rail transportation of the units over long distances; reducing the cost of housing by increasing the amount of factory work and decreasing the amount of work at the building site; the possibility of assembling the units in any kind of weather; the use of a roof structure which reduces the height of the unit while it is being transported; assembling the units with an insulating joint between abutting walls; eliminating in large measure overlap of walls which results in great waste of material and is not necessary; the possibility of placing a readily transportable house on a rented lot which is of particular value in communities where land is of very high price; and providing a house with the above features with distributing characteristics similar to those of other factory built products, such as automobiles.

With the foregoing and other objects in view, the invention will be more fully described hereinafter, and will be more particularly pointed out in the claims appended hereto.

In the drawings, wherein like symbols refer to like or corresponding parts throughout the several views—

Figure 1 is a perspective view of one form of house assembled from three of the building units.

Figure 2 is a section taken on the line 2—2 of the Figure 1.

Figure 3 is a diagrammatic view of the units used in Figure 2 showing them disassembled.

Figure 4 is a perspective view of the founda-

tion block assembly employed in the structure of Figures 1 and 2,

Figure 5 is a perspective view showing the first step in the process of building up the house shown in Figures 1 and 2 from the units.

Figure 6 is a fragmentary detail of the hinged roof structure of one of the units shown in Figures 1 and 2.

Figure 7 is a fragmentary detail of the manner of joining the hinged roof sections of two such units as shown in Figures 5 and 6.

Figure 8 is an enlarged fragmentary detail of the peak joint of the roof shown in Figure 7.

Figure 9 is a detail view of the insulating joint employed in connecting walls of the several units, showing the parts disjoined,

Figure 10 is a detail view of the parts of Figure 9 with the joint made,

Figure 11 is a detail view of a modified dove-tail joint with parts disjoined.

Figure 12 is a detail view of the parts of Figure 11 joined and showing the dove-tail filled with a sealing substance,

Figure 13 is a floor plan of a modified house structure incorporating additional building units, and

Figure 14 is a roof plan of a further modification incorporating still more building units.

Referring now to the drawings and particularly to Figure 1, the house here shown is composed of two L-shaped units 20, 21 and a rectangular unit 22. The L-shaped units are placed with their longer sides abutting while the rectangular unit 22 is placed against the shorter sides thereof.

As will be seen by reference to Figure 5 the L-shaped unit 20 is a completely prefabricated building unit. The framework may be either steel or wood and the walls of any suitable material. As the units are built at the factory they are complete with floors, windows, doors etc.

The walls of the units are disposed as shown in Figures 2 and 3 to prevent needless overlapping. With this in view the wall 23 of the unit 20 ends so as to register with the wall 24 of the unit 22.

The inner wall 25 of the unit 20 ends against the side of the inner wall 26 of the unit 22. There is then no overlapping or waste of wall structure and the abutting walls may be secured together by any desirable form of bolt or the like.

Likewise, the outer wall 27 of the unit 21 abuts the end wall 28 of the unit 22. The inner wall 29 of the unit 21 is provided with just sufficient length to complete the end of a room 30 and to hold a door 31 opening into said room.

A post 28' supports open corner of the unit 21.

At the joints between these walls is provided a sealing joint which consists in corresponding grooves in the abutting walls between which is placed a sealing member. Figures 9 and 10 show the joint so made between the wall 28 of the unit 22 and the end of the wall 21 of the unit 21. Corresponding vertical grooves 32 and 33 are let into the abutting edges of the respective walls. A compressible block 34, of rubber or the like, is fitted into these grooves. When the joint is tightened in assembling the units the block 34 is crushed to fill the two grooves completely as shown in Figure 10 thus making a perfect insulating joint between the walls 21 and 28. Similar joints are provided at each of the connecting joints of the house.

Referring now to Figure 6, the unit 22 is shown with its roof in carrying position. The roof structure consists in the transverse brace 35 between outer wall 36 and the inner wall 26 of the unit, the vertical support 37 which rests on the transverse brace 35 and the longitudinal rib 38 which extends the length of the unit and is supported by the vertical members 37. A fixed roof side 39 is held between the block 40 of the wall 36 and the longitudinal rib 38 by a series of braces 41 which are secured at their opposite ends to the block 40 and the rib 38. The upper end of the brace 41 is provided with pivot 42 for a second roof section 43. This section 43 rests on the braces 44 which are pivoted at 42 with the fixed braces 41. The outer end of the movable roof section 43 is reinforced by means of an angle bar 45 which in the folded position shown in Figure 6 rests on the top of the inner wall 26 of the unit. The roof sections have at their pivot point a joint which consists in the cut away section 46 of the fixed roof and the corresponding overlapping section 47 of the movable roof. As shown in Figure 7, when this movable roof section 43 is raised an overlapping joint is formed above the pivot. It will also be seen that a substantial portion of the height of the building unit is removed by folding down this movable roof section. This is highly convenient in transporting the units to the building site. When the units are placed in position for an assembly the movable roof sections of the abutting units are raised. When the wall joints are completed these roof sections will rest against one another and will be prevented by their length from returning to the folded position. As shown in Figures 7 and 8 the angle bars 45 and 48 come together and may be anchored in this position if desired. In addition to this the edges of the roof sections are bevelled and their upper surfaces provided with the corresponding angular locking strips 49 and 50. Over these locking strips when the units are fastened together is placed a peak cap 51 which effectively seals the peak joint of the roof. The two abutting sections now provide an A roof. When the movable sections of the roof are raised there will be left between the two units a diamond shaped space which is filled in by a similar shaped insert 52 which completes the walls of the units. This structure of roof is best carried out by the employment of sheet metal as a roof covering.

When a definite house plan has been adopted and the units obtained a series of foundation blocks 52' are erected or built on the site, as shown in Figure 4. The arrangement of these blocks 52' is such that there will be provided between the blocks passageways into which a

truck or lorry 53 may enter carrying a building unit. The truck 53 is shown in Figure 5 bearing the unit 20 in the passageway 54. The truck centers the unit above the foundation blocks when a series of jacks or the like are placed beneath the overhanging edges of the unit to raise the same and permit the truck to be moved out of the way, after which the jacks are lowered and the unit settled on the foundation blocks 52'. The corresponding unit 21 is carried in the same way on the truck into the passageway 55 and placed with its long side abutting that of the unit 20. The insulating joints will be completed as the units are placed together as also the roof assembly. A rectangular unit 22 is then driven in the remaining passageway 56 and placed on its foundation blocks against the short sides of the units 20 and 21 and the same insulating and roof joints completed. The spaces between the foundation blocks 52' may be filled in or as shown in Figure 1 a base board 57 may be placed completely around the bottom of the assembled units.

It is to be noted, that the units are built with internal walls and openings so as to permit of variations in the plan of assembly. For instance, the units used in forming Figure 2 have such an arrangement. The unit 20 has an open hallway 58 at its inner short end. The outside wall 23 of this unit is provided with a door 59 which in this assembly forms the entrance door of the house. The hall 58 then serves as a communicating way on which open the three end rooms 60, 61 and 62 of the unit 22. At the opposite end of the hall 58 the wall 25 has a similar door 63 which in this case leads into the large room 64 of the unit 21. In Figure 13 there is added to the house the two additional rectangular sections 65 and 66. The entrance to the house is provided for through the hall 67 in the unit 65. The former entrance hall 58 now being only an internal hallway. It will, however, be seen that the addition of the unit 65 and 66 may be accomplished at any time with a very slight amount of labor. In Figure 14 we see in addition to the unit 65 and 66 a pair of units 68 and 69 added to the opposite side of the house forming a corresponding wing. The internal structure of these units which are added from time to time may readily be varied as to the number, size and arrangement of the rooms contained.

In order to render the addition of further units simple, each of the units is provided at its outside corners and along its walls with series of the insulating joint grooves 69 similar to those shown in Figures 9 and 10. Such of these grooves as are not being employed are filled in with some suitable plastic material which may be readily removed in case it is desired to use the groove in forming a joint with a new unit.

With reference to this problem of the sealing joint a modified form of joint is shown in Figures 11 and 12 wherein abutting wall sections 70 and 71 are provided with vertical dove-tailed grooves 72 and 73 respectively. When the joint is brought together and tightened this vertical dove-tailed groove formed by placing the two walls together is filled with plaster 74 or the like which completely seals the joint. In case of disassembly of the units the plaster may be sawed very readily to break the joint.

Another feature contemplated by the present invention relates to the disposition of all rooms required to be connected to water, gas, drains and the like within a single one of these building

units. In the house structure shown in Figure 2 the unit 22 carries all such rooms. For instance, the room 61 may be a bath room, 62 a kitchen and 75 a furnace room. It will then only be necessary to make a single connection with the drain, a single water connection and a single gas connection. The internal piping and connections may all be completed at the factory before shipping units. Of course it will be seen that the wall 10 26 is common to some of the rooms in the other units and so, if desired, water and other connections may be carried into the other units to be supplied through the unit 22. The furnace room 75 is located in the unit 22 which may be 15 designated as the service unit. The heat provided is preferably, for the small house shown, a warm air system in which ducts from the room 75 may carry the warmed air into the other units. The room 75 has built into it the flue 76 and 20 after the roof is attached to the neighboring unit the chimney 77 is placed in position and connected with the flue.

The above described structure then carries out all of the objects stated. All of the work on the 25 units may be completed at some central factory where modern assembly methods will serve to reduce to a minimum the cost of building. At this factory the units will be completely finished as to floors, doors, windows, and fixtures. It is 30 only necessary then to set the foundation blocks 52 in the positions suited to the layout of the units, set units thereon, make the joints between them, and complete outside connections. It will readily be seen that all this may be accomplished 35 within a few hours.

The units are made of such width that they may be carried on standard rail and truck equipment making for ease and quickness in delivery. Also in line with facilitating transportation of 40 the units overall height is considerably diminished by forming the roof in two hinged sections.

Previous prefabricated houses have had to be of unconventional design and therefore lack a very important element of appeal to prospective 45 purchasers. The houses from the above described units have slanted roofs, and are not mere boxes but have graceful lines and readily adapt themselves to many interesting modifications in design.

Such building units as these may readily be 50 exhibited and sold and various types kept in stock in every city, so that once it is decided to change the house structure, by enlarging or modifying, this change may be made in a very short time. It is also quite feasible when it is desired to move 55 from one location to another to dismantle the house and carry it to the new site. This feature is also of a great deal of importance in localities where land is very expensive, as the house may be placed upon a rented lot and moved from one 60 lot to another when necessary.

Of course, if desirable, the units may be arranged end to end instead of abutting sideways and in such a case the small A roof over each unit would be the permanent roof. The two sides of 65 the A in such a case may both be hinged at the sides of the unit to fold over one another for purposes of transportation.

It is obvious that various changes and modifications may be made in the details of construction and design of the above specifically described embodiment of this invention without departing from the spirit thereof, such changes and modifications being restricted only by the scope of the following claims.

75 What is claimed is:

1. A composite building structure, comprising independent building units each having a fixed and a movable roof section, and means for securing the movable roof sections of adjacent building units together to provide a composite roof for 5 the composite building structure.

2. A composite building structure, comprising independent building units each having a fixed and an adjustable roof section, means for securing the adjustable roof sections of adjoining 10 building units together into a composite roof for the composite building structure, and means for sealing the adjoint portions of the building units together into a composite building structure.

3. A composite building structure, comprising 15 a plurality of independently complete building units having wall openings for register with adjacent units in the composite structure and each having a complete roof with an adjustable portion for relative adjustment with the adjustable 20 roof portions of adjacent units to provide a composite roof for the composite building structure.

4. A composite building structure, comprising independent building units each having an A roof with one side section thereof hinged at the peak 25 relatively to the other side section to swing into substantially the plane thereof, and means for securing the free edges of the hinged roof sections of adjacent units to provide a common roof for the composite building structure. 30

5. A composite building structure, comprising independent building units each having an A roof with one side section thereof hinged at the peak relatively to the other side section to swing into substantially the plane thereof, corresponding 35 locking members at the outer edges of said hinged sections to secure together the hinged sections of adjacent units in the raised position.

6. A composite building structure, comprising independent building units each having an A roof 40 with one side section thereof hinged at the peak relatively to the other side section to swing into substantially the plane thereof, corresponding locking flanges on the upper surfaces of the outer edges of the hinged sections abutting when the 45 hinged sections of adjacent units are raised into the plane of the other section, and a cap fitting over said flanges locking the hinged sections together and sealing the joint therebetween.

7. A composite building structure, comprising 50 independent building units each having an A roof with one side thereof hinged at the peak relatively to the other side section to swing substantially into the plane thereof, the upper surface of one of said sides being cut back from the peak for a distance, and the upper surface of said other side extending over the peak for a distance corresponding to said cut back to provide an overlapping joint at the hinge between said sides when the sides are swung into a common plane. 60

8. A composite house structure comprising a number of complete building units, each unit having a complete A roof one section of which is hinged at the peak to form with an adjacent unit of similar structure a larger A roof over the 65 two units.

9. A pair of prefabricated building units comprising each, a floor, corresponding wall structures to provide inner and outer walls, and a slanting roof structure for each unit adapted to 70 join and form an A roof over the two units and each of said roof structures being in two sections hinged together transversely to fold down and reduce the height of the unit for shipping.

10. A pair of building units comprising two 75

- separate structures each having walls and a roof, the walls being complementary to form a larger single structure when the units are brought together, said roofs being secured at an angle other than a right angle to said walls and adapted when the units are brought together to abut at their upper edges to form an A-roof over the two units, said roofs being hinged longitudinally of the unit to allow the upper side of the roof to be folded down to reduce the overall height of the unit for shipping.
11. A composite structure comprising one unit having side walls with flat top edges and end walls with top edges tapering upwardly to a center higher than the side walls, a fixed roof section secured to one side wall and one side of the tapering top edges of the end walls, a movable roof section hingedly secured to the upper edge of said fixed roof section, and a second unit 15 having like side and end walls and fixed and movable roof sections, said units being placed with the movable roof sections adjacent one another and said roof sections being swung upwardly on their 20 hinges into the planes of their respective fixed roof sections, and the upper outer edges of said movable roof sections abutting to complete an A-roof over the two adjacent units.

respective fixed roof sections, and the upper outer edges of said movable roof sections abutting to complete an A-roof over the two adjacent units.

12. A composite structure comprising one unit having side walls with flat top edges and end walls with top edges tapering upwardly to a center higher than the side walls, a fixed roof section secured to one side wall and one side of the tapering top edges of the end walls, a movable roof section hingedly secured to the upper edge 10 of said fixed roof section, a second unit having like side and end walls and fixed and movable roof sections, said units being placed with the movable roof sections adjacent one another and said roof sections being swung upwardly on their 15 hinges into the planes of their respective fixed roof sections, and the upper outer edges of said movable roof sections abutting to complete an A-roof over the two adjacent units, and a diamond shaped insert filling the space at each end 20 of the structure between the raised movable roof sections and the end walls of the units.

KARL H. BRUNNER.
